UNITED STATES PATENT OFFICE.

LAWRENCE CARR, OF OAKLAND, CALIFORNIA.

STOVE-GRATE.

No. 906,101.

Specification of Letters Patent.

Patented Dec. 8, 1908.

Application filed July 3, 1908. Serial No. 441,853.

To all whom it may concern:

Be it known that I, LAWRENCE CARR, a citizen of the United States, residing at Oakland, in the county of Alameda and State of California, have invented certain new and useful Improvements in Stove-Grates; and I do hereby declare the following to be a full, clear, and exact description of the invention, such as will enable others skilled in the art 10 to which it appertains to make and use the same.

This invention relates to new and useful improvements in stove grates and it is the primary object of the invention to provide 15 a novel device of this character wherein a greater draft area is given to the fire bed than is ordinarily afforded by the grates commonly employed.

It is also an object of the invention to provide 20 a novel device of this character wherein the grate is truncated, said grate being employed in conjunction with a perforated hollow member for the passage of draft.

It is also an object of the invention to provide 25 a novel device of this character which is rotatable and supported within the fire chamber of a stove so that the grate may alternately move in a horizontal plane for depositing ashes within the ash box.

It is also an object of the invention to provide 30 a novel device of this character wherein the draft may be effectually controlled by a slide movable across the under surface of the perforated hollow member.

It is also an object of the invention to provide 35 a novel device of this character which will be simple in construction, efficient and advantageous in practice and comparatively inexpensive to manufacture.

With the above and other objects in view 40 the invention consists of the details of construction and in the novel arrangement and combination of parts to be hereinafter more particularly referred to.

In describing the invention in detail, reference will be had to the accompanying drawings forming part of this specification wherein like characters of reference denote corresponding parts in the several views, and in 45 which,

Figure 1 is a sectional view of a stove illustrating the invention applied therein, and, Fig. 2 is a bottom plan view of a hollow perforated member employed in conjunction 50 with the invention.

In the drawings, 1 denotes the fire cham-

ber of a stove and 2 the ash box therebelow, the line of separation between the fire chamber and the ash box being determined by the inwardly projecting flange 3. 60 On this flange 3 rests an annular perforated ring 4 having projecting inwardly from its inner edge and at right angles thereto, the flange 5. The upper edge of this flange 5 is toothed as at 6 and is adapted to be engaged 65 by the gear wheels 7 fixed to the shafts 8. These shafts 8 pass through suitable bearings 9 projecting inwardly of the stove to the exterior of the stove and terminating in the cranked portions 10 whereby the gears 7 70 may be rotated for a purpose to be herein-after referred to.

Arranged above the flange 5 is a second flange 11 depending from the periphery of a circular plate 12. The free edge of this 75 flange 11 is also provided with teeth 13 which rest upon and mesh with the gears 7 before referred to. The plate 12 is provided with a central opening 14 and also has projecting upwardly therefrom the truncated 80 hollow perforated member 15, the base of the member 15 being of greater diameter than the opening 14 and the opening 14 being arranged centrally of the base of the bar 15.

In proximity to the upper end of the truncated bar 15 exteriorly thereof is an annular flange 16 which is engaged by a ring 17 which contacts with the upper surface thereof and depending from the ring 17 are the grate bars 18 which are formed on a downward curve and are secured at their lower ends to a ring 19 which contacts with the outer edge of the circular plate 12. In order to hold the grate bars 18 in position, the upper surface of the ring 17 is engaged by a 90 clamping ring 20 embracing the member 15. 95

It is to be observed that the grate bars 18 are held away from the truncated member 15 and that the fire bed is adapted to contact therewith. This creates a greater area for 100 draft which passes up through the opening 14 within the truncated member 15 and out through the perforations 21 thereof. Thus it is thought to be apparent that by this arrangement a fire of great heat is produced. 105

In order to control the draft passing through the opening 14 the guide way 22 is formed on the under surface of the plate 12 and extends from opposed sides of the opening 14 to the periphery of the said plate. 110 Within this guide way 22 is movable a slide 23 which is adapted to either close or par-

tially close the opening 14 as may be required and in order that the slide may be readily manipulated it passes through an opening in the flange 13 of the plate and in order that it 5 may be easily accessible, it is preferably positioned adjacent the opening 24 of the stove closed by the door 25.

When it is desired to cause the ashes of the fire bed to fall within the ash box 2, it is only 10 necessary that the wheel 7 be rotated alternately, which movement will cause rotation of the plate 12 and the ring 4. This movement will produce sufficient agitation of the fire bed as to assure a deposit of the ashes 15 within the ash box.

I claim:

1. In combination with a stove, a plate mounted therein, said plate having an opening, a hollow perforated member projecting 20 upwardly from the plate around the opening the wall of said member being inwardly bent and having its closed end substantially semi-globular, a flange surrounding the hollow member adjacent its upper end, a ring resting 25 on said flange, grate bars depending from

said ring on a downward curve and terminating adjacent the outer edge of the plate.

2. The combination with a stove, a plate mounted therein, said plate having an opening through its axial center, an integral hollow perforated member projecting upwardly from the plate around the opening, the base 30 of said member being at a distance from the opening and the wall of the member being inwardly curved, a flange arranged around 35 the hollow member and integral therewith, a ring resting on the flange, grate bars depending from said ring and resting on the plate, said grate bars being inwardly curved and a clamping ring surrounding the upper end of 40 the hollow perforated member adapted to hold the ring seated on the flange on the hollow member.

In testimony whereof I have signed my name to this specification in the presence of 45 two subscribing witnesses.

LAWRENCE CARR.
